DESIGN FOR A BATHTUB OVERFLOW VACUUM CAP

Wade V. Heare, Los Angeles, Calif.

Application August 11, 1941, Serial No. 102,783

Term of patent 7 years

To all whom it may concern:

Be it known that I, Wade V. Heare, a citizen of the United States of America, residing at Los Angeles, in the county of Los Angeles and State of California, have invented a new, original, and ornamental Design for Bathtub Overflow Vacuum Caps, of which the following is a specification, reference being had to the accompanying drawing, forming part thereof.

Fig. 1 is a front elevational view of a bathtub overflow vacuum cap, showing my new design.

Fig. 2 is a plan view of the cap.

Fig. 3 is a horizontal section taken on the line 3—3 of Fig. 1.

I claim:

The ornamental design for a bathtub overflow vacuum cap, as shown.

WADE V. HEARE.
